John L. Benty, Chicago, Ill., assignor to The Dole Valve Company, Morton Grove, Ill., a corporation of Illinois

Filed Apr. 25, 1960, Ser. No. 60,300

Term of patent 14 years

(Cl. D2—3)

FIG. 3

The dominant features of the design reside in the portions shown in full lines.

I claim:

The ornamental design for a liquid dispenser or similar article, substantially as shown and described.
